UNITED STATES PATENT OFFICE.

JOSEPH J. WESLEY, OF HACKENSACK, NEW JERSEY, ASSIGNOR TO METROPOLITAN SWITCH-BOARD COMPANY, A CORPORATION OF NEW JERSEY.

PANEL-BOARD.

No. 926,372.

Specification of Letters Patent. Patented June 29, 1909.

Application filed April 7, 1909. Serial No. 488,465.

To all whom it may concern:

Be it known that I, JOSEPH J. WESLEY, a citizen of the United States, residing at the city of Hackensack, in the county of Bergen and State of New Jersey, have invented certain new and useful Improvements in Panel-Boards, of which the following is a full, clear, and exact description.

This invention relates to panel boards of the type adapted to be inset in the wall of a building, and from which branch or distribution circuits are led to the various localities of a given floor or section of the building. The panel board contains the switches by which these branch or distribution circuits are controlled, and also includes fuses or protective devices for the circuits. Sometimes these switches of the panel board are intended to be left permanently closed or opened through long intervals, the usual control of their circuits being intended to be effected by separate local switches and devices. In this case the panel board is not disturbed except occasionally by a person in authority, such as a janitor of the building. In other installations, however, the panel board contains the switches which are manipulated by everyone for securing the desired control of the various circuits. This promiscuous access to the panel board on the part of every sort of person, has the disadvantage that it invites tampering and damage; it being evident that very serious damage might be ignorantly done from trivial causes, such as establishing short circuits between the mains. Or damage might result from inserting an improper fuse, if this is free to be done by any person. On account of these various reasons, it is much better to exclude promiscuous access on the part of everybody to the fuses and mains of the panel board. It is the purpose of my present invention to so exclude promiscuous access to the fuses and mains of the panel board, but permit it to the operating switches. The latter may be of the snap or wall type under these circumstances, which are substantially proof against any bad effects from the handling of mischievous, careless or ignorant persons.

With these and other objects in view my invention consists in the features of construction and combination as hereinafter set forth and claimed.

In the drawings: Figure 1 is a front elevation of a panel board embodying the principle

ples of my invention; Fig. 2 is a transverse sectional view, the section being taken on the line II—II of Fig. 3, and Fig. 3 is a front view, with the covers, etc., removed to show the interior of the panel box.

Referring to the drawings in which like parts are designated by the same reference sign, 1 denotes a box or housing which is let into the wall of a building in the usual way.

2 denotes a fixed or permanent rim ordinarily made of wooden boards or molding, the same forming a frame or lintel for a central door 3. The door 3 is conveniently hinged at 4 to one of the sides of the rim 2.

5 designates a box of square or rectangular section which is received within the box 1 and constitutes the main supporting frame or base of the panel board parts. This box 5 is best made of insulating material and has a width, height and position corresponding to that of the door 3.

6 designates bus-bars within the box 5, and 7 indicates branch conductors which lead from the bus-bars 6 to the switches 8.

9, 9, designate terminals for receiving fuses in the circuits of the switches 8. In accordance with the present invention the switches 8 are disposed in a compact group at the center of the box 5, preferably lying along the outlines of a square, concentric with the larger square established by the box 5. The fuse terminals 9 lie entirely outside this inner square.

I make use of the switches 8 as bases to support a shallow box or pan 10 which is received within the box 5 in substantially centered relation corresponding to the inner square above referred to which conforms to the area occupied by said switches 8. Within the door 3 there is a second hinged door 12 of a size and position to lie directly over the pan 10. The push buttons or operating means 13 of the switches 8, project through the bottom face of the pan 10 and are therefore exposed when the cover 12 is swung back for this purpose. The door or cover 12 is simply latched to permit free access to the switches by anyone who so desires. It is evident, however, that this access to the interior of the pan 10 does not give access to the mains or to the fuses or to any other parts which might be injured by mischievous treatment. The outer door or cover 3 opens to expose the fuse terminals 9 and permits access to all the parts of the panel board.

This door is preferably locked with a key, for which purpose a keyhole 14 is illustrated in the drawing.

What I claim is:—

1. A panel board comprising a panel box and a door adapted to close over the same, said door having an interior door which can be freely opened to uncover a restricted area of the panel board, switches controlling the branch circuits of the panel board and located in said restricted area, and a pan overlying said switches to cover all the switches and the bus-bars of the panel board when said inner door is opened.
2. A panel board comprising a panel box and a door adapted to close over the same, a key operated lock for securing said door, an interior door opening freely within said first mentioned door to uncover a restricted area of the panel board, switches controlling the branch circuits of the panel board and located in said restricted area, and a pan overlying said switches to cover all the switches and the bus-bars of the panel board when said inner door is opened.
3. A panel board comprising a panel box and a door adapted to close over the same, said door having an interior door which can be freely opened to uncover a restricted area of the panel board, two-button inclosed switches controlling the branch circuits of the panel board and located in said restricted area, and a pan supported by said switches

and overlying the same to cover all the switches and the bus-bars of the panel board 35 when said inner door is opened.

4. A panel board comprising a panel box and a door adapted to close over the same, said door having a concentrically located smaller hinged interior door which can be 40 freely opened to uncover a restricted area of the panel board, switches controlling the branch circuits of the panel board and located in said restricted area, and a pan overlying said switches to cover all the switches 45 and the bus-bars of the panel board, when said inner door is opened.

5. A panel board comprising a panel box and a door adapted to close over the same, said door having an interior door which can be freely opened to uncover a restricted area of the panel board, two-button snap switches 50 controlling the branch circuits of the panel board and located in said restricted area, and a pan overlying said switches to cover the 55 same and the bus-bars of the panel board when said inner door is opened, said pan having holes through which the buttons of said switches are exposed.

In witness whereof, I subscribe my signature, in the presence of two witnesses.

JOSEPH J. WESLEY.
